Julius S. P. Sullivan, of Somerville Mass.
Letter Patent No 2331. Dated June 5, 1866.

Design for the handle of a spoon.
The Schedule referred to in this Letter Patent and making part of the same
To all whom it may concern:

Be it known that I, Julius S. P. Sullivan, of Somerville, in the County of Middlesex, and State of Massachusetts have invented or produced a new and ornamental design or configuration for spoon handles, fork handles, etc., and I do hereby declare that the following, taken in connection with the drawings, which accompany and form part of this specification, is a description of the design sufficient to enable those skilled in the art to practice it.

This design is intended for the ornamentation of spoon handles, fork handles, etc. It is shown in the accompanying drawing as applied to a spoon handle, Figure 1, exhibiting the front and Figure 2, the back of the handle.

The design consists in a double bead, or moulding, the outer member of which a is wider or larger than the inner member b. a, is provided at the left, or end of the handle, with an ornament, and about where the handle joins the body of the spoon or fork, either on the front or back, or both, a luminal ornament d, is provided where they merge into said body. Between the mouldings, the surface of the handle is finished in convex form.

I claim the design for ornamentation of spoon handles, fork handles, etc., as shown in the drawings.

Witness,

J. B. Crosby,
A. H. Tatner

Julius S. P. Sullivan.
